UNITED STATES PATENT OFFICE.

ALANSON McD. GRAY, OF ELIZABETH, NEW JERSEY.

APPARATUS FOR MOLDING WAX.

SPECIFICATION forming part of Letters Patent No. 658,235, dated July 10, 1900.

Application filed November 28, 1899. Serial No. 738,575. (No model.)

To all whom it may concern:

Be it known that I, ALANSON McD. GRAY, a citizen of the United States, residing at No. 445 South Broad street, Elizabeth, county of Union, State of New Jersey, have invented certain new and useful Improvements in Apparatus for Molding Wax and other Materials, of which the following is a specification.

While the invention herein set forth is capable of use in the molding of many materials which are reduced to a fluid condition by heat and run into molds, where they set or are chilled to the condition of a solid, it is designed more particularly for molding paraffin-wax into cakes for handling and shipping.

The invention comprises the use of molds or receptacles set up in a series in alternation with hollow plates, which may form the side walls of the mold and in which the cooling medium is contained or circulated for the purpose of chilling the contents of the mold.

In carrying out the invention I may utilize the frame, abutments, and ram of an ordinary filter-press, the molds being constructed so as to be mounted upon the ordinary side rails of such a press in the same manner as are the ordinary filter-plates, and the chilling-plates may be similarly constructed to be mounted in the same way in alternation with the molds.

In the accompanying drawings, Figure 1 is a plan view; Fig. 2, a side elevation; Fig. 3, a cross-section on the line 3 3 of Fig. 2; Fig. 4, a detached view of one of the molds; Fig. 5, a detached view of one of the hollow chilling-plates with its side broken away.

A may be the ordinary hydraulic cylinder; B, its ram; C, the abutment, and D D the side rails or portions of an ordinary filter-plate.

The molds E may consist merely of castings having vertical sides e e, connected at the bottom by a horizontal bottom piece e', thus forming a rectangular cavity for the reception of the wax or other material to be molded. Preferably I divide this space equally by a center piece e², which divides it into two molding-cavities of equal capacity. On the outer side of each vertical portion e are formed ordinary ears or lugs e³, which rest upon the side rails D D of the press. The chilling-plate F may consist of an open rectangular cast-iron frame f, formed at the ends with lugs

f' and having its sides closed by sheet-iron covers f², riveted on. A cooling medium, as water or refrigerated brine, may be introduced at the pipe f³ and discharged at f⁴. By preference arms f⁵ project from the top and bottom bars of the plate to direct the cooling medium in a sinuous path.

The chilling-plates F and molds E are slung upon the side bars of the press in alternation, as indicated in Figs. 1 and 2, and the assemblage of molds and plates set up closely by a hydraulic cylinder. The several inlet-pipes f³ of the chilling-plates may be connected by flexible tubes, as rubber hose, f⁶, with a common supply-pipe f⁷, while the several outlet-pipes f⁴ may discharge into a trough G or otherwise, as may be desired.

The melted wax may be delivered into the molds in any desired or suitable manner; but preferably I prefer to arrange above the press a common pipe H, to which is connected over each compartment of each mold a faucet I. When the molds have been filled, the wax or other material therein is quickly chilled and soon solidifies. The ram of the press is then run back, the molds and plates separated by sliding them upon the side bars, and the cakes of wax or other material removed from the molds. In the case of paraffin-wax and most other materials that may be molded into cakes, as described, the surface exposed to the atmosphere is somewhat rough and, owing to shrinkage, is depressed or concave. These uneven ends of the cakes may be sawed off, so as to leave the cakes of uniform size. The molds are entirely open at the sides to permit of the ready removal of the cakes.

All the chilling-plates (except those at the ends of the assemblage of molds and plates) may be constructed as in Fig. 5—that is to say, at their ends they are of the same height as the end bars e e of the molds and between their ends are of less height. The end plates are throughout their length of the same height as the molds, as seen in Fig. 3, where F' indicates the left-hand end plate. There is therefore an edge or guard around the assemblage of molds and plates extending above the central parts of the plates, as indicated by the dotted line x in Fig. 2, which permits of liquid wax overflowing one mold running into another or which renders unnecessary

that the liquid should be run directly into the molds and not strike upon the depressed upper edges of the plates. I am not therefore obliged to use a separate pipe or cock, as I, 5 for filling each mold, but may deliver the liquid to the molds in any manner or from one or more cocks, which should desirably be of such capacity as to quickly fill all the molds. If there is a shallow layer of the liquid above the depressed top edges of the plates, it will entirely or largely sink or re-cede because of contraction of the wax in cooling. Of course the end plates and some of the intermediate plates need be but closing- 15 plates and not have a circulation of a cooling medium through them; but I prefer that all plates should be chilling-plates, as the material will solidify more rapidly and the capacity of the apparatus be correspondingly 20 greater.

The molds are shown entirely open at the top; but they are not necessarily so, as the cake may be and in practice is removed laterally. The top opening of the molds need 25 only, therefore, be of such character as to properly admit the material. I prefer that they shall be rectangular, as they pack readily and economically in rectangular packages and may be readily handled and shipped. It is 30 obvious that the mere mechanical details of construction of the molds and chilled plates may be varied without departing from my invention and also that the parts of a filter-press described are not essentials, since the 35 plates and molds may be assembled and set up against each other in other ways.

I claim as invention—

1. A flat open-sided mold permanently closed at its bottom and ends and having an 40 opening at the top for the introduction of the material, in combination with independent removable hollow chilling-plates forming the closing sides thereof, a support upon which the mold and plates are mounted and upon 45 which they are independently movable laterally or flatwise, and means for circulating a cooling medium through the plates, whereby the mold and plates may be pressed together thus closing the mold at its sides and separated after the material in the mold is chilled or solidified to permit the removal of the cake laterally from the mold.

2. The combination of a series of flat open-sided molds permanently closed at their bottoms and ends and having openings at the 55 top for the introduction of material, a series of hollow flat chilling-plates arranged in alternation with the molds and forming the closing sides thereof, a support upon which the molds and plates are mounted and upon 60 which they are independently movable laterally or flatwise, means for setting up or pressing the assemblage of molds and plates together and also releasing them from pressure to permit their separation, and means for circulating a cooling medium through the

plates, whereby after the material is chilled or solidified the molds and plates may be separated and the cakes removed laterally from the molds.

3. The combination of a series of flat open-sided molds, open at the top, a series of hollow flat chilling-plates arranged in alternation with the molds and forming the closing sides thereof, means for setting up or pressing the assemblage of molds and plates together, means for circulating a cooling medium through the plates and means for introducing into the molds fluid material to be chilled and molded.

4. The combination of the abutment, side bars and pressure-cylinder, a series of flat open-sided molds open at the top and adapted to be hung vertically upon the side bars, a series of hollow flat chilling-plates adapted to be similarly hung and arranged in alternation with the molds and forming the closing sides thereof, a supply-pipe with outlets in proper relation to the top openings of the molds to deliver melted material thereto when the molds and plates are pressed up together and means whereby a cooling medium may be circulated through the plates.

5. The combination of the abutment, side bars and pressure device, of a series of flat 95 molds open at the top and both sides and divided by a partition to form two molding-compartments, a series of hollow flat chilling-plates arranged in alternation with the molds and forming the closed sides thereof, the assemblage of plates and molds being hung vertically upon the side bars and adapted to be pressed together, a supply-pipe arranged above the assemblage of plates and molds and having a series of outlets arranged one above 100 each mold-compartment to deliver the melted material to the mold, and means for circulating a cooling medium through the hollow chilling-plates.

6. The combination of the flat open-sided 110 molds, open at the top, the hollow chilling-plates arranged in alternation therewith and forming the closing sides thereof, the frame or bars D D upon which the assemblage of 115 molds and plates are mounted, means for pressing the assemblage of molds and plates together, a common supply-pipe for carrying a cooling medium, and flexible hose connections between such supply-pipe and the respective hollow chilling-plates for the introduction thereinto of a cooling medium.

7. The combination of a series of flat open-sided molds having openings at the top for the introduction of material, a series of plates arranged in alternation with the molds and having the central parts of their upper edges depressed below the outer edges of the molds, end plates whose upper edges are as high as the sides of the molds, means for setting up or pressing the plates together for the introduction into the molds of the material to be 125 molded and then releasing the molds and

plates from pressure to permit their separation for the extraction of the cakes from the molds.

8. The combination of a series of flat open-sided molds having openings at the top for the introduction of material, a series of hollow plates arranged in alternation with the molds and having the central parts of their upper edges depressed below the outer edges of the molds, end plates whose upper edges are as high as the sides of the molds, means for setting up or pressing the plates together for the introduction into the molds of the material to be molded, then releasing the molds and plates from pressure to permit their separation for the extraction of the cakes from the molds, and means for circulating a cooling medium through the hollow plates.

9. The combination of an assemblage of molds open at the side and also at the top for the introduction of material and plates closing the molds at the side, means for setting up or pressing the assemblage of molds and plates together for the introduction into the molds of the material to be molded and for releasing them from pressure to permit the separation of the molds and plates and the extraction of the cakes from the molds.

10. The combination of an assemblage of molds open at the side and also at the top for the introduction of material, and hollow plates closing the molds at the side, means for setting up or pressing the assemblage of molds and plates together for the introduc-

tion into the molds of the material to be 35 molded and for releasing them from pressure to permit the separation of the molds and plates and the extraction of the cakes from the molds, and means for circulating a cooling medium through the hollow plates.

11. The combination of the abutment, side rail, cylinder and ram, of an assemblage of molds open at the sides and also at the top for the introduction of material, and plates closing the sides of the molds whereby the assemblage of molds and plates may be pressed up together by the action of the power-cylinder, the molds filled, the pressure then relieved, the molds and plates separated and the cakes extracted from the molds.

12. The combination with the abutment, side rail, cylinder and ram of an assemblage of molds open at the sides and also at the top for the introduction of material, hollow plates closing the sides of the molds whereby the assemblage of molds and plates may be pressed up together by the action of the power-cylinder, the molds filled, the pressure then relieved, the molds and plates separated, and the cakes extracted from the molds, and means 55 for circulating a cooling medium through the hollow plates.

In testimony whereof I have hereunto subscribed my name.

ALANSON McD. GRAY.
